Primary Examiner — Charles D Hanson(74) *Attorney, Agent, or Firm* — Stephen D. Carver**CLAIM**

The ornamental design for a lumbar interbody implant, as shown and described.

DESCRIPTION

FIG. 1 is a frontal isometric view of our new lumbar interbody implant, showing our new design;

FIG. 2 is a front elevational view thereof;

FIG. 3 is a rear elevational view;

FIG. 4 is a left side elevational view taken from a position to the right of FIG. 1;

FIG. 5 is a right side elevational view thereof;

FIG. 6 is a top plan view thereof;

FIG. 7 is a bottom plan view thereof; and,

FIG. 8 is a rear isometric view thereof.

1 Claim, 5 Drawing Sheets(56)
